WINDOW STRUCTURE

Michael J. Tracy, Robertson, Mo.

Application October 30, 1950, Serial No. 192,940

5 Claims. (Cl. 20—42)

1

This invention relates generally to window structures and more specifically to window structures of the louvre sash type, the predominant object of the invention being to provide a window structure which is of such improved construction and arrangement that manual adjustment of one sash of the window structure to open or closed positions by bodily moving said one sash will result in automatic adjusting of another sash of the window structure in a predetermined sequence of operations.

Fig. 1 is an elevational view of a window structure made in accordance with this invention and looking toward the outer side of the window structure.

Fig. 2-A is a fragmentary, vertical section taken on line 2—2 of Fig. 1 and showing the upper portion of the window structure.

Fig. 2-B is a fragmentary, vertical section taken on line 2—2 of Fig. 1 and showing the lower portion of the window structure.

Fig. 3 is a fragmentary, vertical section similar to Fig. 2-A but showing parts of the window structure in changed positions.

Fig. 4 is an enlarged horizontal section taken on line 4—4 of Fig. 2-A.

Fig. 5 is a fragmentary, vertical section taken on line 5—5 of Fig. 3.

Fig. 6 is a fragmentary, vertical section of the upper portion of the window structure.

Fig. 7 is a horizontal section taken on line 7—7 of Fig. 2-A.

Fig. 8 is a perspective view of a part of the improved window structure.

Fig. 9 is a horizontal section taken on line 9—9 of Fig. 2-A.

In the drawings, wherein is shown for purposes of illustration, merely, one embodiment of the invention, 1 designates the frame of a window structure which is designated generally by the reference character A. The window frame 1 is of rectangular shape, as is shown in Fig. 1, being composed of a sill portion 1a, a head portion 1b, and opposed jamb portions 1c. The opposed jamb portions 1c have formed therein at their inner faces channelways 2 that extend longitudinally of said jamb portions from top to bottom thereof.

In the embodiment of the invention illustrated in the drawings, the window frame 1 has associated therewith three window sashes which are designated by the reference characters 3a, 3b, and 3c, said sashes comprising each a sash frame 4 in which is suitably glazed a pane of glass, or other material. The upper and lower frame members

2

of each such frame are shaped in cross-section as is shown to good advantage in Fig. 2-A; that is to say, the upper frame member includes a portion 5 which extends from the inner face to the outer face of said upper frame member and has a recess 6 formed therein that extends longitudinally of said upper frame member, there also being a flange 7 which is located at the inner portion of said upper frame member and projects upwardly from said portion 5. The lower frame member of each sash includes a portion 8 which extends from the inner face to the outer face of said lower frame member and has a recess 8' formed therein that extends longitudinally of said lower frame member, said frame portion 8 being provided at its outer portion with a flange 9 which projects downwardly from said portion 8 of said lower frame member. By referring to Figs. 4, 7, and 9 it will be noted that the opposed side members of each sash frame have a cross-sectional shape which is similar to the cross-sectional shape of the lower member of the sash frame, the side members of each sash including each a portion 10 from which is extended outwardly a flange 11.

Disposed for sliding movement in the channelways 2 which are formed in the opposed jamb portions of the window frame 1 is a pair of bars 12, said bars being only slightly shorter in length than height of the jamb portions of the window frame 1. The upper sash 3a is pivotally supported at its opposite sides and adjacent to its top by means of pivot elements 13, it being noted that at a side of the frame of the sash 3a, said sash frame has fixed thereto by means of fastening devices 14 an elongated element 15, there being a similar elongated element secured to the frame of the sash 3a at the opposite side of said sash frame. The pivot element 13 at each side of the window frame 1 includes a portion 13a of reduced diameter which is disposed in an opening formed through the related elongated element 15 and the outer end portion of this reduced portion 13' is riveted over, as indicated at 13b so as to secure said pivot element to said elongated element 15.

Mounted for pivotal movement on the pivot element 13 at each side of the window structure is a latch member 16, said latch member having an outwardly projected nose portion 16a at its upper portion and being provided at its lower portion with a notch 16b. The latch member 16 is provided at its lower portion also with a forwardly extended portion 16c, and the pivot element 13 at each side of the window structure projects into an opening formed through the upper

portion of its related latch member, the latch member being swingable about said pivot element. Each latch member 16 is arranged within a housing 17 which is shaped in cross-section as is shown in Fig. 4 and is secured fixedly in place relative to the window frame by means of fastening devices 18, each of said housings having a wall 17' in which a slot 19 is formed and the related pivot element 13 being extended through the slot. Each latch member contacts, at a side face thereof, with its related bar 12, as is shown in Fig. 5, and each bar 12 is provided with a pin 20 which extends therefrom, said pin serving a function to be hereinafter set forth. The housing 17 at each side of the window structure is 5 provided with an inclined wall portion 21 which serves as a cam that moves the lower portion of the latch member in a manner and for a purpose to be hereinafter explained.

The upper sash 3a has pivotally attached to its frame at each side thereof by a pivot element 22 an arm 23, the opposite end of said arm being pivotally connected by means of a pivot element 24 to a support 25 which is fixed to the window frame by fastening devices 26 (Fig. 9), the bar 12 being adapted for sliding movement relative to said support 25. Each arm 23 has mounted thereon a pin 27 on which is rotatably supported a roller 28 that cooperates with the related member 29 in a manner and for a purpose to be hereinafter set forth. The members 29 are preferably though not necessarily, formed of sheet metal and each thereof is secured by fastening devices 30 to one of the bars 12, each member 29 comprising an outstanding, upwardly inclined flange 31, a second outstanding, upwardly inclined flange 32, a vertical flange 33, and a bottom flange 34. It is to be noted that the fastening devices 30 are extended through slots 35 formed through portions of the member 29, and as a result of this arrangement said member 29 may be adjusted vertically, if necessary, so as to position it in proper position for use.

The lower sash 3c is supported for inward swinging movement by a hinge 36, as is shown in Fig. 2-B, and said lower sash is provided at each side thereof with an arm 37, each of said arms being pivotally attached at one end thereof to the frame of the lower sash 3c by means of a pivot element 38 and being pivotally attached at its opposite end to the bar 12 at the corresponding side of the window structure by means of a pivot element 39.

In the embodiment of the invention disclosed herein the intermediate sash 3b is fixedly and nonadjustably supported by the window frame 1. However, it is to be understood that all of the sashes may be supported for adjustment if desired, and the sequence of operation of the sashes may be varied so as to suit different requirements.

In describing the use of a window structure constructed in accordance with this invention, it will be assumed that the lower and upper sashes are in their closed positions, in which positions of said lower and upper sashes the bars 12 will be in elevated positions that locate the pins 20 in the raised position in which the pin 20 is shown in Fig. 2-A. If the lower sash 3c now be drawn inwardly at its top to an open position the bars 12 will be moved downwardly, the inward swinging movement to which the lower sash is subjected being translated into downward movement of the bars 12 through the instrumentality of the arms 37. During initial movement of the lower sash 3c, however, no movement is imparted to the

upper sash 3a because the latch members 16 are unlatched from the pins 20 and the bars 12 may move downwardly without imparting movement to said upper sash. As a result of this arrangement the lower sash may be adjusted to a partially opened position while the upper sash is maintained in a closed position. If, now, it is desired to adjust both the lower sash and the upper sash to opened positions, the inward, opening movement of the lower sash is continued and eventually the pins 20 on the downwardly moving bars 12 will contact with the extensions 16c of the latch members 16 and as said latch members start to move downwardly with the bars 12, the rounded faces 16' thereof acting against the inclined wall portions 21 of the housings 17 will cause the latch members 16 to swing on the pivot elements 13 so as to seat the pins 20 deep in the notches 16b of the latch members. The upper portion of the upper sash is now latched to the bars 12 by the latch members 16 and continued downward movement of the bars 12 as a result of continued inward opening movement of the lower sash will swing the lower portion of the upper sash outwardly to the open position of said upper sash.

It is important to note that when the upper sash is closed the pivot elements 22 and 24 at opposite ends of the arms 23 associated with said upper sash are approximately on dead center. However, as the bars 12 reach certain positions in their downward movement where the upper sash is about to start its opening movement, the inclined flanges 31 of the members 29, that are fixed to the bars 12, engage the rollers 28 which are supported by the arms 23 associated with the upper sash so as to produce a camming effect that moves the upper ends of said arms 23 outwardly a sufficient distance to eliminate the dead center relation of the pivot elements 22 and 24 and permit the upper sash to be moved to its outward, open position. Also, when the upper sash is in its closed position the rollers 28 are in contact with faces of the vertical flanges 33 of the members 29 whereby said upper sash is locked in such closed position.

In performing the operation of closing the upper and lower sashes of the window structure of this invention, the lower sash is moved toward its closed position and such movement of said lower sash will subject the bars 12 to upward movement, and because the upper sash is latched to the bars 12 by cooperation of the latch members 16 and the pins 20 the upper sash will move upwardly and will be adjusted toward its closed position. Immediately before the upper sash reaches its upward and closed position the nose portions 16a of the latch members 16 contact with abutments 40 (see Fig. 6) formed on walls of the housings 17, and continued upward movement of the bars 12 and the latch members 16 after this contact is made will result in the latch members being swung on their pivots 13 in the direction indicated by the arrow in Fig. 6. This will disengage the latch members 16 from the pins 20 of the bars 12 and the bars may be moved an additional distance upwardly so as to permit the lower sash to be closed. When the latch members 16 have been disengaged from the pins 20, as explained above, the opposed arms 23 of the upper sash have reached a position where the upper sash is closed and where the pivot elements 22 and 24 of said arms 23 are on dead center. Thus the upper sash is maintained in its elevated and closed position by the arms 23, and said upper sash is locked in such position because of the fact that

5

the rollers 28 of the pins 27 which are mounted on the arms 23 are now positioned behind the vertical flanges 33 of the members 29 so as to prevent outward movement of said arms 23.

I claim:

1. A window structure comprising a window frame, an upper sash and a lower sash associated with said window frame, said sashes being of the louvre type and being adapted for swinging adjustment to open and closed positions with respect to said window frame, a member supported for sliding movement by said window frame, an arm pivoted at one end thereof to said sliding member and at the opposite end thereof to said lower sash for connecting said sliding member and said lower sash for cooperation, a second arm pivoted at one end thereof to said upper sash and at the opposite end thereof to a fixed part of the window structure for supporting said upper sash for swinging movement, a latch member pivotally supported at an end thereof in a fixed location by said upper sash and movable into and out of latching engagement with respect to a latch-receiving element supported by said slideable member, and cam means fixed to said slideable member for imparting initial movement to said second arm at the beginning of opening movement of said upper sash.

2. A window structure comprising a window frame, an upper sash and a lower sash associated with said window frame, said sashes being of the louvre type and being adapted for swinging adjustment to open and closed positions with respect to said window frame, a member supported for sliding movement by said window frame, an arm pivoted at one end thereof to said sliding member and at the opposite end thereof to said lower sash for connecting said sliding member and said lower sash for cooperation, a second arm pivoted at one end thereof to said upper sash and at the opposite end thereof to a fixed part of the window structure for supporting said upper sash for swinging movement, a latch member pivotally supported at an end thereof in a fixed position by said upper sash and movable into and out of latching engagement with respect to a latch-receiving element supported by said slideable member, and means fixed to said slideable member and including a part having an inclined face for imparting initial movement to said second arm at the beginning of opening movement of said upper sash.

3. A window structure comprising a window frame, an upper sash and a lower sash associated with said window frame, said sashes being of the louvre type and being adapted for swinging adjustment to open and closed positions with respect to said window frame, a member supported for sliding movement by said window frame, an arm pivoted at one end thereof to said sliding member and at the opposite end thereof to said lower sash for connecting said sliding member and said lower sash for cooperation, a second arm pivoted at one end thereof to said upper sash and at the opposite end thereof to a fixed part of the window structure for supporting said upper sash for swinging movement, a latch member pivotally supported at an end thereof in a fixed location by said upper sash and movable into and out of latching engagement with respect to a latch-receiving element supported by said slideable member, and means fixed to said slideable member and including a part having an inclined face for imparting initial movement to said second arm at the beginning of opening movement of said upper sash.

6

sash, the last-mentioned means including a flange which is engaged by said element supported by said second arm for locking said second arm against pivotal movement when said upper sash is in its locked position.

4. A window structure comprising a window frame, an upper sash and a lower sash associated with said window frame, said sashes being of the louvre type and being adapted for swinging adjustment to open and closed positions with respect to said window frame, a member supported for sliding movement by said window frame, an arm pivoted at one end thereof to said sliding member and at the opposite end thereof to said lower sash for connecting said sliding member and said lower sash for cooperation, a second arm pivoted at one end thereof to said upper sash and at the opposite end thereof to a fixed part of the window structure for supporting said upper sash for swinging movement, a latch member pivotally supported at an end thereof in a fixed location by said upper sash and movable into and out of latching engagement with respect to a latch-receiving element supported by said slideable member, and means fixed to said slideable member and including a part having an inclined face for imparting initial movement to said second arm at the beginning of opening movement of said upper sash, the last-mentioned means including a vertical flange which is engaged by said element supported by said second arm for locking said second arm against pivotal movement when said upper sash is in its locked position.

5. A window structure comprising a window frame, an upper sash and a lower sash associated with said window frame, said sashes being of the louvre type and being adapted for swinging adjustment to open and closed positions with respect to said window frame, a member supported for sliding movement by said window frame, an arm pivoted at one end thereof to said sliding member and at the opposite end thereof to said lower sash for connecting said sliding member and said lower sash for cooperation, a second arm pivoted at one end thereof to said upper sash and at the opposite end thereof to a fixed part of the window structure for supporting said upper sash for swinging movement, a latch member pivotally supported at an end thereof in a fixed location by said upper sash and movable into and out of latching engagement with respect to a latch-receiving element supported by said slideable member, and means fixed to said slideable member and including a part having an inclined face for imparting initial movement to said second arm at the beginning of opening movement of said upper sash, the last-mentioned means including a vertical flange which is engaged by said element supported by said second arm for locking said second arm against pivotal movement when said upper sash is in its locked position, said vertical flange having an upwardly inclined portion at the top thereof.

MICHAEL J. TRACY.
